[57] CLAIM

The ornamental design for cutout insulator, as shown and described.

DESCRIPTION

FIG. 1 is a side elevational view of a cutout insulator showing my new design, the opposite side being a mirror image;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view of a second embodiment of my new design, the opposite side being a mirror image;

FIG. 7 is a front elevational view thereof;

FIG. 8 is a rear elevational view thereof;

FIG. 9 is a top plan view thereof;

FIG. 10 is a bottom plan view thereof;

FIG. 11 is a side elevational view of a third embodiment of my new design, the opposite side being a mirror image;

FIG. 12 is a front elevational view thereof;

FIG. 13 is a rear elevational view thereof;

FIG. 14 is a top plain view thereof;

FIG. 15 is a bottom plan view thereof.
